CONVERTIBLE GARMENT

Alexander Chessin, Yonkers, N. Y.

Application March 6, 1941, Serial No. 381,932

2 Claims. (Cl. 2—213)

The present invention relates to convertible garments and, more particularly, to a culotte convertible into a skirt and vice versa.

Conversion of an ordinary skirt into a culotte, although repeatedly attempted, did not succeed because there is no material in an ordinary skirt to provide for the crotch portion indispensable in a culotte. Unless a special form of skirt is devised, the conversion, to be successful, should be reversed, i. e. it should be from a culotte into a skirt, and the problem, then, is to take care of the crotch portion of the culotte which becomes surplusage in the skirt. Accordingly, it is one of the purposes of the present invention to base the convertible garment on a standard culotte pattern. It is also a purpose of the present invention to provide the crotch from both, the front and the rear panels of the garment, i. e. the material which becomes surplusage in the conversion from culotte into skirt is distributed, being divided into two parts of less bulk and, therefore, more easily taken care of. Another purpose of the present invention is to conceal the crotch portion from view when the culotte is converted into a skirt, at the same time creating no bulges and allowing the skirt to fall naturally, smoothly and neatly, with no indication whatsoever that it is a converted garment and not a bona fide skirt. Still another purpose is to prevent sagging of the skirt because of the weight of the crotch surplusage by properly supporting the crotch portions which are concealed underneath the front and the rear panels of the garment, especially when the conversion is effected by means of metal slide connectors, popularly known as "zippers," the weight of which, unless properly supported, would increase the sagging tendency due to the weight of the surplus material of the no longer necessary crotch portions. A further purpose of the present invention is to allow the conversion from culotte to skirt and vice versa to be made by the person wearing the garment without taking it off or appearing undressed while making the change. The last mentioned feature presents a definite and very considerable advantage. It is also a purpose of the present invention to make the garment, whether as a culotte or as a skirt, have an attractive and stylish appearance. A still further purpose of the invention is to provide a garment which is shadow proof, as a skirt thus necessitating no slip which would be in the way when the garment is in the form of a culotte. Other objects will become apparent from the specification which follows.

While the invention as here illustrated shows a garment convertible from culotte to skirt, i. e. a comparatively short skirt, it is obvious that it is quite as readily applicable to garments convertible from long skirts into trousers or slacks, from robes into pajamas and vice versa, the only difference between such garments being the length and the material of the garment.

Referring to the drawings, Figure 1 is a complete lay out of the pattern used for making a garment embodying the present invention and comprising four panels, two front and two rear panels. Figure 2 is a plan view of the back panels sewn together along the crotch outline when the garment is arranged as a skirt. Figure 3 is a similar view of the front panels when sewn together along the crotch outline. Figure 4 is a detail showing one of the crotch supporting pieces. Figure 5 is a perspective view of another pattern wherein the corresponding front and rear panels are formed in a single piece instead of separately. This figure is in a reduced size as compared to Figure 1. Figure 6 is a front view of the garment as a skirt. Figure 7 is a plan view of this skirt opened along one of its extreme outer seams and laid out flat showing the construction inside. Figure 8 is a cross section along the line 8—8 of Figure 6. Figure 9 is a cross section along the line 9—9 of Figure 6. Both, Figures 8 and 9 are enlarged in scale. Figure 10 is a front view of the garment as a culotte. Figure 11 is a plan view similar to Figure 7 but when the garment is in the form of a culotte. Figures 12 and 13 are, respectively, cross sections along the lines 12—12 and 13—13 of Figure 10, enlarged.

Referring to the figures in detail, 1 designates the rear right panel, 2 the rear left panel, 3 the front left panel and 4 the front right panel. The words "left" and "right" refer to the sides corresponding to the left and right legs respectively. It will be noted that the corresponding front and rear panels are identical in shape, so that the garment has exactly the same appearance whether viewed from the front or from the rear. Therefore, Figures 6 and 10 respectively are also rear views of the skirt and culotte. In Figure 1, 5 and 5' designate, respectively, the crotch defining curves on panels 1 and 2; likewise, 6 and 6' designate the crotch defining curves on panels 3 and 4, respectively. As shown in Figure 2, the two rear panels 1 and 2 are sewn together along the edges formed by the curves 5 and 5', thus making up the crotch seam 18. Likewise, the panels 3 and 4 are sewn together along the

edges formed by the curves 6 and 6', making up the crotch seam 19. Going back to Figure 1, 7 and 7' are, respectively, the extreme outer side lines of the panels 1 and 4, defining the edges which, when sewn together form the extreme outer seams of the garment on one side thereof. Likewise, 8 and 8' are, respectively the extreme outer side lines of panels 2 and 3 which, when sewn together form the extreme outer seam of the garment on the other side thereof. At the top of the garment, an opening is provided between the panels 2 and 3, operated by a slide connector one element of which, 9, is secured to the panel 2 and a cooperating element, 9', is secured to the panel 3. From the meeting point 16 of the curves 5, 5', 6, 6', down, the edges 10 (of panel 1), 10' (of panel 2), 11 (of panel 4) and 11' (of panel 3) are also provided with slide connectors with mutually cooperating elements, to wit: 12 on edge 10, 13 on edge 10', 14 on edge 11 and 15 on edge 11'. The garment's waist line is designated by the numeral 17. The garment is provided with a set of box pleats in front and in the rear, each set comprising a central or median pleat 20 and two pleats 21, 21, disposed symmetrically thereto.

The construction of the median pleat 20 requires some elucidation. It will be noted that the panels 1 and 3 are slightly wider than the panels 2 and 4. The dash-dot lines 28, 29 and 30 indicate folding lines of the garment. The difference in width between the panels 1 and 3 and the panels 2 and 4 is twice the width between the folding lines 28 and 29. The reason for this construction is that, in forming the median pleat 20, the panels 2 and 4 are folded once only, namely, along the lines 30, whereas the panels 1 and 3 are folded twice, once along the line 29 (which is an inner fold) and again along the line 28 (which is an outer fold). Both, at the front and at the rear, the panels present folds which are adjacent to one another along the respective median lines of the skirt, namely, the folded panels 1 and 2 form adjacent lines 29 and 30 along the rear median line of the skirt (or, which is the same thing, the median line of the median pleat) and the folded panels 3 and 4 form adjacent lines 29 and 30 along the front median line of the skirt. This construction is necessary to enable the garment to hang properly, as I have found after considerable experimentation. Unless the garment when in the form of a skirt is provided with the so constructed median pleat, the panels 2 and 4 will project forward of the panels 1 and 3 along the median line, front or back, of the skirt, at the folding lines 30, giving the skirt an ungainly appearance. The crotch supporting piece 22, shown separately in Figure 4, are sewn to the garment along the lines 23, on the inside, thus also forming a lining for the garment. Preferably, they are made of silk in order to improve the fit of the garment. Obviously, the crotch portions may be supported in several other ways, as, for instance, by a strap secured to the waist line of the garment. When supported as shown in the drawings, the weight of the crotch portions is taken up from the waist line also, the pieces 22 being sewn to the garment at that line also. The crotch material is secured to the supporting pieces 22 by any convenient detachable means, as, for instance, the snap fastener 24, one element whereof is secured to the piece 22 and the other to the crotch portion at the point 16. It will be noted that the seams 26 and 27 on Figures 7 and 11 are the seams formed when the extreme outer edges 7 and 7' are sewn together and the

edges 8 and 8' are sewn together, the first one of these seams (26) being shown as actually appearing in the garment and the other (27) severed in the process of developing the garment, as previously explained, to disclose the inside construction. As shown in Figures 6 and 10, the garment is provided with a belting 25 along the waist line 17.

It will be clear from the drawings that when the garment is to be formed into a culotte, the element 12 of one of the slide connectors above referred to is connected to the element 15, and the element 13 is connected to the element 14 (see Figure 12). When the garment is to be in the form of a skirt, the element 12 is connected to the element 13, and the element 14 to the element 15 (see Figure 8). In Figure 7, one of the supporting pieces 22 is shown partly folded to better illustrate the construction. Also, one of the crotch portions is shown as partly folded to illustrate what happens to this surplage of material when the garment is formed into a skirt. When the garment is formed into a culotte, the two crotch portions are secured to one another at the point 16 by the same snap fastener 24.

The modification illustrated in Figure 5 differs from the embodiment described above only in one respect, namely, it has no seams 26, 27, because the panels 1 and 4 are made of one piece, and the panels 2 and 3 are similarly made of one piece. This construction, however, is unusual. Common practice dictates the use of separate panels such as are illustrated in Figure 1.

Naturally, the slide connectors shown in the illustrations are not the only means for separably connecting the several panels. The present invention contemplates any other equivalent means for accomplishing the same result. Slide connectors are here shown because they are the quickest means for making the conversion from one type to the other of the garment and because they are very popular.

As was stated in the preamble, the invention may be readily applied to a number of other garments, converting, for instance, pajamas into a robe, or vice versa; trousers or slacks into a correspondingly long skirt and vice versa; in general, a garment on the skirt principle into one on the trouser principle. Obvious variations of the present invention, including some additions, omissions, or changes in detail, would not affect the general character and scope of the invention and it is to be understood that such variations are within the contemplation of the present invention and need not be further illustrated. It may not be amiss, however, to emphasize some of the salient features and advantages of the present invention. One is that the wearer can easily make the conversion from culotte to skirt and vice versa without removing the garment, merely disengaging some of the slide connector elements and re-engaging them to different elements, as above explained. Thus, a woman riding to her office on a bicycle, for example, can arrange the garment as a culotte while riding and quickly change it into a skirt upon arriving at her office, without the necessity of disrobing. The central pleat (20) is important not only because it insures the correct hanging of the skirt, as above explained, but also because it renders the garment shadow proof, the other pleats being added mainly for the sake of better appearance.

I claim:

1. A convertible garment comprising a pair of front and a pair of rear panels, the top edges

whereof form the waist line of said garment, the inner edges of said panels having substantially straight upper and lower portions and a downwardly and outwardly curved connecting portion, the front panels and the rear panels respectively being sewn together along said upper straight and said connecting curved portions, forming the central body seams of the garment and each front panel being permanently united with the corresponding rear panel at the sides of the garment, means for separably uniting each front panel with the corresponding rear panel along said lower portions of the inner edges, said means also serving to separably unite the front panels and the rear panels respectively along the said lower portions of said inner edges, front and rear crotch portions formed by the front and rear panels respectively when the front panels are united to their corresponding rear panels along their inner edges, said crotch portions having a separable fastener thereon and being detachably secured in place underneath said panels by means of a member supported from said waist line and carrying a cooperating fastener when said front and rear panels respectively are united along their inner edges and the garment is worn as a skirt.

2. A convertible garment comprising a pair of front and a pair of rear panels, the top edges whereof form the waist line of said garment, 30

the inner edges of said panels having substantially straight upper and lower portions and a downwardly and outwardly curved connecting portion, the front panels and the rear panels respectively being sewn together along said upper straight and said connecting curved portions, forming the central body seams of the garment, and each front panel being permanently united with the corresponding rear panel at the sides of the garment, means for separably uniting each front panel with the corresponding rear panel along said lower portions of the inner edges, said means also serving to separably unite the front panels and the rear panels respectively along said lower portions of said inner edges, front and rear crotch portions formed by the front and rear panels respectively when the front panels are united to their corresponding rear panels along their inner edges, and a lining member for said panels secured to said garment at said waist line and along its longitudinal edges to the adjacent panel, and carrying one element of a separable fastener at the lower portion thereof, said crotch portions carrying a cooperating element of said fastener and being detachably secured to said lining member when said front and rear panels respectively are united along their inner edges and the garment is worn as a skirt.

ALEXANDER CHESSIN.
